DIFFERENTIAL FEED DEVICE FOR SEWING MACHINES

Fritz Ebert, Oberndorf-on-the-Neckar, Germany,
assignor to Mauser-Werke A. G., Oberndorf-on-the-Neckar, Germany, a joint-stock company of Germany

Application December 30, 1935, Serial No. 56,808
In Germany December 31, 1934

8 Claims. (Cl. 112—208)

The invention has for its object a differential feed device for sewing machines, the device being intended for carrier arm sewing machines.

The present invention has for one of its objects to permit the machine to be run at a much higher speed than has been hitherto possible with carrier arm sewing machines having a differential feed, namely, at 4000 revolutions.

The high speed and output of applicant's machine are primarily attributed to the improved arrangement of the driving members, hereinafter described and claimed.

According to the present invention the drive of the main feeding device is carried in the pedestal of the sewing machine frame, that is, in the most stable part of the machine frame. Furthermore, the intermediate drive which is controlled by the drive of the main feed is located in the carrier arm from which the differential feed is actuated, and is carried close to the pedestal of the sewing machine frame and thus on a stable position of the carrier arm.

As driving means for the main feed, there is used a lever oscillated directly from the main spindle of the sewing machine, in the direction of the carrier arm, which lever, by means of a connecting rod, drives in the direction of the carrier arm an intermediate lever rocking about a transverse axis. On this intermediate lever is carried both the member which moves the main feed device longitudinally, and the member by which the differential feed device is moved longitudinally, and means are provided to adjust both feed devices independently of each other as regards the length of stroke of the feed. The main adjustment of the feed stroke takes place by shifting the position at which the connecting rod is attached to the driving lever of the main feed, with respect to the axis of rotation thereof, that is, by altering the transmission ratio.

On the intermediate lever which drives, both the main and the differential feed device, is carried the member for the longitudinal displacement of the former viz., the main feeding frame, at points as far removed from each other as the carrier arm permits, whereby an exceedingly stable construction is obtained.

The main feed member can be adjusted with respect to its frame in the longitudinal direction of the carrier arm. In the same way, the differential feed member can also be adjusted longitudinally, care being taken to prevent in both cases, a rotation of the part in question.

The object of the present invention is more

fully explained by way of example in the accompanying drawings.

Figs. 1 and 2 are a side view and a plan respectively of the complete differential feed device with sectionized casing and carrier arm.

Fig. 3 is a cross-section through the rear part of the carrier arm.

Fig. 4 shows a detail which prevents rotation.

Fig. 5 shows in perspective the whole differential feed device.

Figs. 6 and 7 are sectional elevation and plan respectively of the feed device guide in a second embodiment.

The sewing machine is provided with the usual carrier arm 1 in which for the most part is carried the differential feed device. The main feeding member 2 is located between the two differential feed members 3. The feed members 2 and 3 carry out the usual reciprocating movements in the longitudinal direction of the carrier arm 1. 15 and at the same time upward and downward movements. The latter are produced in a known manner and their control device is consequently not described.

The feed devices 2 and 3 are driven by the main spindle 4 located transversely to the carrier arm 1, and which first drives a lever 5 which, in turn, drives both the feed devices 2 and 3, through suitable lever mechanism.

The main spindle 4 drives the main driving lever 5 by means of an eccentric 6 through a joint 7. The driving lever 5 is a double armed lever which oscillates in the direction of the carrier arm 1 of the sewing machine, on an intermediate spindle 8 serving for the drive of the looper. The intermediate spindle 8 is carried in the housing or pedestal 9 of the sewing machine. The driving lever 5, rocks by means of a link 10 a lever arm 11 which is also oscillatably swung in the direction of the carrier arm 1 about a horizontal transverse axis 12. The latter is mounted close to the pedestal 9 of the sewing machine housing in the carrier arm 1. In order to vary the stroke of the feeding devices 2 and 3, that is to be able to alter the amount of the feeding movement, the drive thereof is adjustable, this being accomplished by the pin 13, by means of which the link 10 is connected with the downwardly projecting arm of the driving lever 5, being adjustable towards and away from the pivot 50 8 thereof, whereby the transmission ratio is altered. To this end, the connecting pin 13 is adjustable in a slot 14 of the driving lever 5.

Both the feed devices 2 and 3 are driven by this intermediate driving lever 11. To control

- the main feed device 2, its operating connection rod 15 is carried oscillatably on horizontal cross pins 16 mounted on the intermediate lever 11 which is made double armed, for this purpose.
- 5 In order to obtain a particularly stable arrangement, the connecting rod 15 is forked and is opened out as wide as the carrier arm 1 permits. Its two bearings 17 are oscillatable about the pins 16, one of which is supported directly in the intermediate lever 11 itself and the other in a short arm 18 extending from the boss 19 of the lever 11. The lever arms 11 and 18 together form with the boss a U-shaped lever which is adapted to be oscillatably swung about the transverse spindle 12.

15 The connecting rod 15 is fitted detachably on the carrier rod 20 of the feed device 2, so that the rod 20 can be moved backward and forward for the purpose of adjusting the main feed device 2 after loosening the fixing device. The carrier rod 20 is displaceable longitudinally in a carrier sleeve 21 of the differential feed device 3, which latter is supported non-rotatably in the slot in the carrier arm 1. In the embodiment shown, the connecting rod 15 is axially slotted at the outer end and is firmly clamped in a detachable manner on the carrier rod 20, by means of clamps 22.

If now the driving lever 5 carries out its oscillating movements, the carrier rod 20 of the main feed device 2 is moved backwards and forwards in the longitudinal direction of the carrier arm 1, that is in the direction of feed of the material, and is at the same time moved up and down in known manner by means of the lifting device.

30 For driving the differential feed piece 3 the intermediate driving part 11, is provided with a further arm 23 directed upward, and fitted on the boss 19 thereof. This drives by means of a connecting rod 24 the differential feed piece 3, and is for this purpose connected with the carrier sleeve 21 thereof. In order to be able to vary the feeding stroke of the differential feed piece 3 independently, the transmission ratio can be varied similarly as in the case of the main feed drive. To this end, the pin 25 by means of which the connecting rod 24 is attached to the third arm 23 of the intermediate driving lever 11, can be adjusted with respect to its axis of rotation 12 by means of a slot 26.

45 Furthermore, means are provided in order to move the differential feed device 3 with respect to the main feed device 2.

To this end, there is provided at the rear extremity of the carrier sleeve 21 a two-part coupling comprising two sleeves 27, 28 serving as a guide in the adjustment. Both sleeves 27, 28 are slotted axially and by means of clamps 29 are firmly clamped on the carrier 21. The sleeve 27 is connected to the rod 24 and after loosening the sleeve 27 from the carrier sleeve 21, this, and with it, the differential feeder piece 3 can be shifted backward or forward.

50 In order to make a fresh adjustment unnecessary, to prevent any relative turning movement of the sleeves, the front sleeve 28 is provided with a tooth 30 which engages loosely, and is adapted to move longitudinally, in a corresponding slot 31 of the inner sleeve 27. It is thus possible to shift the differential feed piece 3 without a fresh adjustment being necessary.

The main feed device 2 is carried in any suitable manner in the differential feeder carrier sleeve 21. In the embodiment shown in Figs. 6 and 7, it is secured by means of a projection 32

engaging a slot 33 in the carrier sleeve 21 of the differential feed member 3. A different construction is shown in Figs. 1 and 2. In this a member 34 is let into the connecting rod 15 of the main feed device 2 and fixed on the end 5 surface of the carrier rod 20 thereof by means of a screw 35, at the time of assembly, whereby said member need only be positioned once.

I claim:—

1. Differential work feed mechanism for sewing machines, comprising a pedestal, a carrier arm extending therefrom, a main work feed device, a differential work feed device, an intermediate lever mounted in the carrier arm and rocking about an axis transverse thereto and located near the pedestal, a main drive shaft journalled in the pedestal, a lever oscillated by said main drive shaft and having a segmental arm, a link connecting said intermediate lever to the segmental arm, means for fixing the link to said segmental arm at an adjustable distance from the axis of oscillation of said lever, connections between the intermediate lever and the main and auxiliary feed devices, said devices and connections reciprocating longitudinally of the carrier arm, and means in the connections between the intermediate lever and the differential work feed device for independently adjusting the stroke length of said device.

2. Differential work feed mechanism for sewing machines comprising a pedestal, a carrier arm extending therefrom, a main work feed device, a differential work feed device, an intermediate lever mounted in the carrier arm and rocking about an axis transverse thereto and located near the pedestal, a main drive shaft journalled in the pedestal, a lever oscillated by said main drive shaft, means for driving the intermediate lever with an adjustable stroke amplitude from the oscillatory lever, connections between the intermediate lever and the main and auxiliary feed devices, said devices and connections reciprocating longitudinally of the carrier arm, and means in the connections between the intermediate lever and the differential work feed device for independently adjusting the stroke length of said device.

3. Differential work feed mechanism for sewing machines, comprising a pedestal, a carrier arm extending therefrom, a main work feed device, a differential work feed device, an intermediate lever mounted in the carrier arm and rocking about an axis transverse thereto and located near the pedestal, a main drive shaft journalled in the pedestal, a lever oscillated by said main drive shaft, means for driving the intermediate lever with an adjustable stroke amplitude from the oscillatory lever, connections between the intermediate lever and the main feed device comprising a connecting rod having its end nearer the pedestal in the form of a fork the limbs of which are jointed at spaced points to the intermediate lever, connections between the intermediate lever and the differential work feed device, and means in said last mentioned connections for independently adjusting the stroke length of said device.

4. Differential work feed mechanism for sewing machines, comprising a pedestal, a carrier arm extending therefrom, a main work feed device, a differential work feed device, an intermediate lever mounted in the carrier arm and rocking about an axis transverse thereto and located near the pedestal, a main drive shaft journalled in the pedestal, a lever oscillated by

said main drive shaft, means for driving the intermediate lever with an adjustable stroke amplitude from the oscillatory lever, connections between the intermediate lever and the main work feed device, connections between the intermediate lever and the differential feed device comprising a connecting rod jointed to the intermediate lever, and means for adjusting the distance of the joint from the axis of rocking of the intermediate lever.

5. Differential work feed mechanism for sewing machines, comprising a pedestal, a carrier arm extending therefrom, a main work feed device, a differential work feed device, an intermediate lever mounted in the carrier arm and rocking about an axis transverse thereto and located near the pedestal, a main drive shaft journalled in the pedestal, a lever oscillated by said main drive shaft, means for driving the intermediate lever with an adjustable stroke amplitude from the oscillatory lever, connections between the intermediate lever and the main feed device comprising a connecting rod having its end nearer the pedestal in the form of a fork the limbs of which are jointed at spaced points to the intermediate lever, connections between the intermediate lever and the differential feed device comprising a connecting rod jointed to the intermediate lever, and means for adjusting the distance of the joint from the axis of the intermediate lever.

6. Mechanism according to claim 5, in which the main work feed device is connected to its

connecting rod by means of a carrier rod which also supports the differential work feed device, and the latter is operated by its connecting rod through coupling means comprising a pair of clamp sleeves on the carrier rod one of which sleeves is fixed to the differential work feed device and the other to its connecting rod, means being provided to prevent relative rotation between the sleeves when their axial spacing is adjusted by their clamp means.

7. Mechanism according to claim 5, in which the main feed device is connected to its connecting rod by means of a carrier rod, and the differential work feed device is carried by a sleeve slidably mounted on said carrier rod and adjustably connected to the connecting rod operating said differential work feed device, means being provided in the carrier sleeve to guide the main work feed device longitudinally of the said sleeve.

8. Mechanism according to claim 5 in which the main feed device is connected to its connecting rod by means of a carrier rod, and the differential work feed device is carried by a sleeve slidably mounted on said carrier rod and adjustably connected to the connecting rod operating said differential work feed device, means being provided in the connecting rod of the main work feed device for attaching the carrier rod to said connecting rod with capacity for their mutual axial adjustment with prevention of relative rotation.

FRITZ EBERT.
